Pearson, Meriam, of Leominster State of Massachusetts,

Letters Patent,

The schedule referred to in these Letters Patent and making part of the same containing a description in the words of the said Patent. Meriam himself of his improvement, in the "Cut, Pick, and Set Machine".

To all persons to whom these presents shall come. Be it known that I, Reuben Meriam, of Leominster in the County of Worcester and Commonwealth of Massachusetts, have invented a new & useful improvement in the machine for manufacturing Filling Parcs used in Carding Machines known by the name of "Cut, Pick, & Set Machine". The machine on which my improvement is made, was formerly patented by a Mess Whittlemore. The following is a full and exact description as far as the case will allow, of the improvement of said Whittlemore's machine which I claim to have invented.

The improvement consists in effecting the said motion of the carriage which holds the bather, in a more gentle & perfect manner, so that the operation may be greatly accelerated and the machine at the same time less liable to get out of order.

This is done by a wheel of suitable size, firmly attached to a horizontal arbor which turns on from center, passing through the center of the wheel, which wheel in the annexed drawing is marked A, through this wheel and near its circumference, pins are inserted at equal distances, which are in number equal to double the number, of rows of teeth in the filling. These pins are of unequal length, the first pin barely passing through the wheel, the second passing through as much more as it is necessary for the bather to be moved side ways in order to receive the next tooth. The pins continue to

to lengthen in the same proportion half round the wheel, and then are shortened in the same proportion on the other half of the wheel to the pins first mentioned, except that there are two long pins of the same length, standing together, and two short pins of the same length standing together, at the longest and shortest ends.

The above mentioned wheel is put in motion by another wheel marked B, in the annexed drawing which is firmly attached to an arbor turning with equal speed with the main arbor of the machine, on the outer edge or circumference of the last mentioned wheel are a suitable number of teeth placed in the form and operating in the manner of an endspur screw, which take hold of the cog wheel, marked C, in the drawing, which cog wheel is attached to the arbor passing through the wheel A, these teeth pass about half round the wheel in the annexed drawing, on the other half of the circumference of the wheel is a groove, which holds the wheel A in its proper place while the card tooth is inserted, The ends of the pins inserted in the wheel marked A pass against a plain placed perpendicularly nearly in the form of a segment of a circle, which is marked in the annexed drawing D, in the centre of this plain the operating pin becomes stationary when it is necessary for the carriage to be so, the upper part only of the plain appears in the drawing, the plain is kept close to the pins, by a string or weight suspended by a cord fastened to the carriage and passing over a loose pulley, Thus by half the revolution of the wheel A the teeth are set once across the card from left to right, and by the other half of the revolution, another row of teeth is set from right to left.

The plain is attached to a slide in the carriage marked E in the drawing it is flat and moveable and in a short distance, on the back side of the slide not seen in the drawing is a small wheel attached to an arbor and turned in centre firmly attached to the carriage, through which wheel are inserted a sufficient number of small pins the

the ends of which are made to press against another plain attached to the slide. This last mentioned wheel is put in motion by two hands on opposite sides of the wheel A, and the operation of its screw pins against the plain, moves the plain D, sideways, so as to effect at will in the card.

What I claim as the above specified principle of moving the carriage. The other parts of my machine are not materially different from Whittlemore's. The carriage of his machine and of all others, known to me, are moved by hands, alternately, setting into a rach.

The motion of the carriage may also be effected by two planes: one plane on each side of the wheel A and half of the pins reversed, so that one half shall press against one plane and the other half of the above described plane only would be necessary, and springs must be made to operate alternately so as to keep the planes close to the pins. This last mentioned improvement I also claim as my own invention, and have it in contemplation to apply the same to the said machine.
